ATTORNEY.

UNITED STATES PATENT OFFICE

2,627,444

DESK FOR ATTACHMENT TO FURNITURE
DRAWERS

Samuel David Altman, New York, N. Y.

Application January 18, 1952, Serial No. 267,143

2 Claims. (Cl. 311—17)

1

This invention relates to an attachable device wherewith any usual article of furniture equipped with drawers, as a chiffonier, dresser, or drawer chest, can be converted to serve as a desk, the invention being particularly advantageous in situations wherein a desk or table is not available or cannot be had for lack of floor space.

The principal object of the invention is to provide an improved device for the aforesaid purpose, which will be salable at low cost, rigid, 10 strong, durable, reliable, and conveniently and efficiently utilizable.

Another object is to provide such device with simplified, efficient, and improved means for its installation in connection with any usual furniture drawer.

A further object is to provide such device with simplified, efficient, and improved means for rendering the desk board thereof readily and conveniently inoperative and completely out of sight during non-use and for restoring it to operative condition in connection with the drawer to which it is attached.

Other objects and advantages will hereinafter appear.

In the accompanying drawings,

Fig. 1 is a general elevational view, partly in cross-section, showing the attachable desk constituting the invention, as it appears when in extended operative position, in connection with a drawer of an article of furniture with which it is used.

Fig. 2 is a top plan view of the attachable desk shown in Fig. 1, in an enlarged scale.

Fig. 3 is a side elevational view, in a substantially full size scale, illustrating the mechanism and parts of the invention, as they appear when the desk is in operative state.

Fig. 4 is a rear elevational view of the device, as seen in Figs. 1, 3.

The device 1 constituting the invention includes a utilitarian desk table board 2, to the rear end of which are secured, by means of bolts 3, downwardly extending posts 4, each of which is provided with a laterally projecting arm 5 having a journal 6 mounted in a bearing 7 of a fitting 8, the latter being securable, as shown in Figs. 3, 4, by means of screws 9 to the interior side 10 of the wall 11 of a drawer 12 of any conveniently available article of furniture, as the chiffonier 13 illustrated in Fig. 1. When the desk device 1 is securely attached and installed in the operative condition shown in Fig. 1, in connection with a drawer 12 of furniture 13, its table board 2 may be swung about its hinges 6, 7 in the operative position shown, in which condition it is firmly and securely supported in the extended state shown, by its rear portion resting firmly upon the upper rim of the front drawer wall 11 and being anchored by its posts 4 and the fittings 8 fastened

to said wall. When the table 2 is not being used it may be swung backwardly about its hinges 6, 7, as indicated by the arrows, to a location entirely within the drawer 12, as shown by the dash and dot lines, in which position the table 2 is retained more firmly by abutting against projecting heads 14 of screws 15 threaded in the wall 11, and the table 2 thus assumes a horizontal inoperative location within the drawer 12.

Variations may be resorted to within the scope of the invention, and the appended claims.

Having thus described my invention, I claim:

1. The combination of a board for attachment to the front wall of a living room furniture drawer to serve as a desk, said drawer being of a width and depth ample to receive said board in a horizontal disposition, a pair of fittings securable to the interior surface of said wall, said board carrying a pair of posts at its rear end, said posts being hinged about a fixed axis to said fittings whereby said board may be swung backwardly about said hinging to a horizontal inoperative location interiorly of said drawer, said board being swingable forwardly about said hinging from said inoperative horizontal location to an operative disposition exteriorly of said drawer, and said board when in said operative disposition being supported by said fixed axis hinging and by resting on the upper rim of said wall.
2. A desk for attachment to the front wall of a furniture drawer having the combination of a table board, a pair of fittings securable to the interior surface of said wall, said board carrying a pair of posts at its rear end, said posts being hinged about a fixed axis to said fittings whereby said board may be swung backwardly about said hinging to a horizontal inoperative location interiorly of said drawer, said board being swingable forwardly about said hinging from said inoperative location to an operative disposition exteriorly of said drawer, said board when in said operative disposition being supported by said posts and fittings and by resting on the upper rim of said wall, the interior surface of said wall having an abutment, and said board bearing against said abutment when it is in said inoperative location.

SAMUEL DAVID ALTMAN.
